UNITED STATES PATENT OFFICE.

LOUIS H. BRINKMAN, OF GLEN RIDGE, NEW JERSEY, ASSIGNOR TO BALL ROLLED TUBE CORPORATION, A CORPORATION OF NEW YORK.

METHOD AND APPARATUS FOR DRAWING METAL.

1,360,088.

Specification of Letters Patent. Patented Nov. 23, 1920.

Application filed May 25, 1918. Serial No. 236,477.

To all whom it may concern:

Be it known that I, LOUIS H. BRINKMAN, a citizen of the United States, residing at Glen Ridge, Essex county, and State of New Jersey, have invented new and useful Improvements in Methods and Apparatus for Drawing Metal, of which the following is a specification:

This invention relates to apparatus and methods for drawing metal.

Where hot metal is drawn through a die, particularly where thin tubes are drawn, if the metal remains too hot after it has gone through the die, the pull of the draw head is apt to stretch or distort the metal or even to part it.

It is one object of the present invention to provide means for cooling the metal after it has passed through the die so that the disadvantages referred to are avoided.

A further object of the invention is to provide a method for drawing metal to avoid the above mentioned disadvantages.

A further object of the invention is to provide a structure of mandrel whereby improved cooling conditions are obtained.

Other and ancillary objects of the invention will appear hereinafter.

In the accompanying drawings which illustrate the invention—

Figure 1 is a side elevation of apparatus embodying the invention;

Fig. 2 is a top plan view of the apparatus of Fig. 1;

Fig. 3 is a view on an enlarged scale showing the die and mandrel, some of the parts being broken away, in vertical axial section;

Fig. 4 is a side elevation showing the head end of the mandrel, certain of the parts being broken away;

Fig. 5 is an end elevation looking from the right of Fig. 4; and

Fig. 6 is a section on the line 6—6 of Fig. 4.

Referring to the drawings and first more particularly to Figs. 1 and 2, 1 is a draw bench on one end of which is mounted a rotary electric motor 2 on the frame of which the ball die mechanism 3 is journaled as hereinafter referred to. To the left of this mechanism I provide a furnace, such as a gas furnace 4 mounted on legs 5 and having a series of gas pipes 6. This furnace is hollow so as to permit the insertion of a mandrel 7

therethrough when tubes are being drawn and so as to receive the tube 8 to be heated and drawn. Movable along a track way on the draw bench at the rear of the motor is a draw head 10 and a following block 11. The following block is provided with a pair of tongs 12 having gripping jaws 13 adapted to grip on to a plug or other suitable means 14 secured in the end of the tube 8 to be drawn, while the other extremity of the tongs is provided with toggle links 15 and a hook 15' connecting the tongs to the draw head 10, which is in turn provided with the pivotal hook 16 having a handle 17 by means of which it is lifted into and out of engagement with an endless chain 18 passing over sprocket wheels 19 and 20 mounted at the ends of the draw bench. The chain may be driven by means of a suitable rotary electric motor 21 geared to the sprocket wheel 20 by gear wheels 22.

The mandrel is supported at one end in the head of a pillow block 23. The mandrel throughout the greater portion of its length is preferably of considerably less diameter than the tube to be drawn, and extends 80 through the furnace 4 to the ball die mechanism proper and is provided with an enlarged head or plug 24 lying within the ball die mechanism and of the desired inner diameter of the finished tube, which will be 85 referred to more in detail hereinafter.

Referring to Fig. 3 of the drawing, a hollow spindle 29 is journaled in the end heads of the frame of the motor 2 and is secured to the rotary member of the motor 2 so as to be turned thereby. A rotating supporting frame or die block 33 is threaded and keyed on to the extremity of the spindle and is provided with an opening in which suitable die ball supporting parts such as relatively 95 adjustable die cheek plates 34 and 35 are secured, the cheek plate 35 being preferably threaded into the die block 33, the cheek plate 34 being keyed to the said die block so as to slide in and out therein. The adjacent 100 surfaces of the two cheek plates form a race way for the die balls 38 and the balls are retained in this race way by means of a retaining ring 39. The cheek plates are secured to the die block 33 and so rotated therewith, but the cheek plate 34 is so keyed to the block that it may slide longitudinally 105 therein for the purpose of varying the di-

ameter of the die which is accomplished by the inclined surface 40 of the cheek plate 34, forcing the balls inward or permitting them to move outward according as this cheek plate is moved toward or away from the cheek plate 35. The adjustment of the cheek plate 34 is accomplished by means of an adjusting device having an annular flange portion 42 threaded on to an annular frame 43 which is keyed to the projection 31 from the motor frame. The adjusting device which is in the form of a cap has an end portion 44 and is provided with an opening 45 in alignment with the hollow spindle 29. The end portion 44 of the adjusting device is intended to thrust inwardly against the cheek plate 34 and in order to avoid friction between this portion and the adjacent cheek plate in adjusting the die while the machine is in operation and to take up any thrust from the die balls, ball bearings 46 are provided. Also ball bearings 47 are provided between the inner end of the die block 33 and the frame 43 for taking up the thrust of the die balls, which will be exerted through the die block and the bearings against the frame of the motor. The adjusting device for varying the diameter of the die may be operated by inserting a suitable tool in the circumferential recesses 49. The cap comprising the end portion 44 being thus rotated, it will, by reason of its screw threaded engagement with the frame 43, be shifted longitudinally. Turning the cap in one direction will unscrew it so that it will move to the left as viewed in Fig. 3, and the corresponding longitudinal shifting of the ring 34 will permit the balls to move outwardly and the diameter of the die to be enlarged. Conversely a reverse longitudinal shifting of the cap and ring 34 by rotating it in the opposite direction, will force the balls inwardly and reduce the diameter of the die. The die cheek plates 34 and 35, which form the race way between them for the die balls, are so arranged to provide an annular passage 60 leading therefrom and communicating with a series of openings or passages 61 leading to the inner surface of the rotary spindle 29. The outer end of the cheek plate 34 is provided with an annular flange 62 projecting radially inward so that the opening through this cheek plate is of less diameter than the inner diameter of the hollow spindle 29. The water is introduced just within this flange by means of a pipe 63 and by reason of the centrifugal force is caused to flow from the point of delivery into the race way, across the race way and through the passages 60 and 61 into the hollow spindle and along the inner surface of the same to a hood 65 from which it may be drained off. The water thus controlled by centrifugal action, cools the die parts,

washes away the scale and at the same time is prevented from coming in contact with the hot metal being drawn.

The apparatus thus far described is similar to that of my Patent No. 1,203,306, issued October 31st, 1916.

Where hot tubes are to be drawn with the apparatus, the mandrel 7 is provided in the form of a hollow tube having the enlarged head 24 hollow and through the hollow mandrel is passed a small tube 57 extending from the tail end of the mandrel and through the same to the enlarged head. This tube is connected up with a suitable source of cooling fluid from which water will be supplied to the interior of the head 24, the end of the tube 57 being screwed into it as shown. The water may pass through holes 70 in the tube 57 to the interior of the mandrel and out through the tail end of the mandrel thus cooling it so it will not become over heated where it passes through the furnace. Also by reason of the communication of the tube 57 with the interior of the head 24, this head will become filled with water which will be ejected through the passages 71, opening at the end of the head, against the plate 72 which is spaced from the end of the mandrel by a shoulder 73 and held in position by a pin 74 extending through the projection 75 from the end of the mandrel head upon which the annular plate 72 is mounted. The jets of water from the passages 71 striking against the plate 72 are directed outwardly against the interior of the tube 8 being drawn. The mandrel is so placed that this water will strike a section of the tube at a point shortly after it has passed under the die balls, cooling the same. This improves the tensile strength of the tube at the point wherein tensile strength is most required, namely, between the draw head and the die or pass. This is of especial importance in drawing thin tubes, where if the tube is hot, the pull necessary to draw the tube through the die may unduly stretch the tube or even part it.

It is also important in the drawing of brass that the cooling fluid be applied upon the inside of the tube for, if applied on the outside, the tube will crack.

While the invention of apparatus has been illustrated in what is considered its best embodiment, and details of a method have been recited, it is to be understood that both the apparatus and method may be varied without departing from its spirit, and therefore the invention of apparatus is not limited to the structure shown in the drawings, nor is the method limited to the precise details recited, the invention being pointed out in the appended claims as required by the patent statutes.

What I claim is—

1. In metal drawing apparatus for draw-

130

ing tubes, the combination with a support including rotary means, for a series of balls adapted to act upon the work, means for rotating said rotary means, balls engaged by said support and means for chilling the work to increase its tensile strength just after it has passed from under said balls, the axis of the die along which the work is drawn being horizontal.

5 6. In metal drawing apparatus for drawing tubes, the combination with a support including rotary means, for a series of balls adapted to act upon the work, means for rotating said rotary means, balls engaged by said support and means for applying a cooling fluid in a jet or spray to the work just after it has passed from under the balls.

10 7. In metal drawing apparatus for drawing tubes, the combination with a support including rotary means, for a series of balls adapted to act upon the work, means for rotating said rotary means, balls engaged by said support and means for applying a cooling fluid to the inside of the tube in a jet or spray just after it has passed from under the balls.

15 8. In metal drawing apparatus for drawing tubes, the combination with a support including rotary means, for a series of balls adapted to act upon the work, means for rotating said rotary means, balls engaged by said support and means for applying a

20 cooling fluid to the inside of the tube in a jet or spray just after it has passed from under the balls.

25 9. In metal drawing apparatus for drawing tubes, the combination with a support including rotary means, for a series of balls adapted to act upon the work, means for rotating said rotary means, balls engaged by said support, a mandrel extending within the tube beneath the balls, and means for

30 supplying a cooling fluid to said mandrel, said mandrel having openings through which said fluid is ejected upon the circumferential walls of the tube being drawn.

35 10. In metal drawing apparatus for drawing tubes, the combination with a support including rotary means, for a series of balls adapted to act upon the work, means for rotating said rotary means, balls engaged by said support, a mandrel extending within the tube beneath the balls, and means for

40 supplying a cooling fluid to said mandrel, said mandrel having openings through which said fluid is ejected upon the circumferential walls of the tube being drawn.

45 11. In metal drawing apparatus for drawing tubes, the combination with a support including rotary means, for a series of balls adapted to act upon the work, means for rotating said rotary means, balls engaged by said support, a mandrel extending within the tube beneath the balls, and means for

50 supplying a cooling fluid to said mandrel, said mandrel having openings through which said fluid is ejected upon the tube being drawn.

55 12. In metal drawing apparatus for drawing tubes, the combination with a support including rotary means, for a series of balls adapted to act upon the work, means for rotating said rotary means, balls engaged by said support, a hollow mandrel extending within the tube beneath the balls, a tube entering through said mandrel and communicating with the portion thereof beneath the balls for supplying fluid thereto, said tube having openings for permitting a portion of the cooling fluid to flow outwardly into the mandrel and said mandrel having openings through which said fluid is ejected upon the tube being drawn.

60 13. The method of reducing tubes which consists in drawing the tube through an annular series of balls, the balls being meanwhile rotated circumferentially about the tube and increasing the tensile strength of the tube between the balls and draw head by chilling the tube.

65 14. The method of reducing tubes which consists in drawing the tube through an annular series of balls, the balls being meanwhile rotated circumferentially about the tube and increasing the tensile strength of the tube between the balls and draw head by applying a cooling fluid thereto.

70 15. The method of reducing tubes which consists in drawing the tube through an annular series of balls, the balls being meanwhile rotated circumferentially about the tube and increasing the tensile strength of the tube between the balls and draw head by applying a cooling fluid to the interior thereof.

75 16. In testimony whereof I have signed this specification this 23rd day of May, 1918.

LOUIS H. BRINKMAN.
